ARMING DEVICE

Henry H. Porter, Silver Spring, Md., assignor to
United States of America as represented by the
Secretary of War

Application December 12, 1946, Serial No. 715,850

3 Claims. (CL. 102—79)

1

This invention relates to a latching device or detent for fuzes and more particularly to an improved arming device for fuses for use with rotating projectiles.

An object of the invention is to provide an arming device which will remain in locking position during the setback or linear accelerating period, when a projectile in which the device is mounted is passing along the bore of a gun, but which will thereafter be released by the action of centrifugal force of the rotating projectile, thereby permitting the projectile to arm after leaving the barrel of the gun.

Another object of the invention is to provide a detent which is of simple design and construction.

A further object of the invention is to provide a detent which may be readily mounted in a projectile or the fuze thereof.

The specific nature of the invention as well as other objects and advantages thereof will be clear from the description of a preferred embodiment as shown in the accompanying drawing, in which:

Figure 1 is a sectional view of a fuze showing the latching device incorporated therein.

Figure 2 is a longitudinal sectional view of the latching device upon an enlarged scale forming a more important part of my invention.

Figure 3 is a transverse sectional view on line 3—3 of Figure 2.

In the drawings, wherein for the purpose of illustration, is shown a preferred embodiment of my invention, the numeral 25 designates a fuze body commonly used on rotating projectiles.

The fuze body is provided with a neck portion 30 for attachment to a projectile and a nose portion 31 for receiving an impact firing pin 28 in a central bore 32.

A centrifugally operated stop plunger 33 is mounted in the nose portion 31 and restrains the firing pin 28 under normal conditions.

Pivoted on a pin 34 within a recess 35 in the body portion 25 is an interrupter gate 27, normally in the path of the firing pin 28.

In flight the interrupter gate will be released to move outwardly by a latching device constituting the present invention; and the stop plunger 33 also will move outwardly leaving a clear path for the firing pin 28 to impinge on a cap contained in the interrupter gate 27 for initiating a powder train in said gate and firing a primer 36 in the fuze body, when impact with a target occurs.

The invention comprises a housing 1 in the form of a hollow cylinder having a thin wall

2

portion 2 integral with a base portion 3. Base portion 3 has a cylindrical passage 4 coaxial with housing 1 and ends with an inside shoulder 5. A recess 6 is provided in one side of cylindrical passage 4 extending from shoulder 5 about one half of the distance along the passage. The passage 4 and recess 6 have the same radial dimension, their axes being offset parallel a sufficient distance to provide the desired depth, the end of recess 6 being beveled as at shoulder 7, all for a purpose to appear later.

A radial pin hole 8 is provided in the base portion 3 in the side opposite recess 6 for properly locating the detent in a fuze body 25, with the recess 6 rearwardly thereof relative to the direction of acceleration.

The inner end of housing 1 is turned in to form a flange 9 defining a passage 10 in axial alignment with passage 4 in base portion 3.

20 A plunger 14 having a shank or body portion 15, with an integral stepped collar 16 and a generally frusto-conical tip portion 17, is provided within housing 1. The shank 15 has a free sliding fit in cylindrical passage 4. Collar 16 fits freely inside thin wall portion 2 of housing 1, and is tapered rearwardly as at 18. A helical spring 20, fitting inside of the thin wall portion 2 of housing 1, surrounding shank 15 of plunger 14, is resiliently engaged between shoulder 5 and collar 16, thereby normally biasing collar 16 against flange 9, with the tip portion 17 projecting out through passage 10. The maximum diameter of the frusto-conical tip portion 17 of plunger 14 is substantially less than that of the passage 10, so that, when the plunger is tilted to one side, there will be no interference between the flange 9 and the frusto-conical portion 17. Recess 6 permits shank 15 to tilt for a purpose to be shown later.

40 The detent assembly is installed in a fuze body 25, with the frusto-conical tip portion 17 of plunger 14 extending into a suitable socket 26 in the side wall of explosive train interrupting gate 27 in the path of movement of firing pin 28 or in the rotor of an auxiliary detonator (not shown), with its axis in radial relation to the fuze in which it is installed, and the frusto-conical tip portion 17 pointing toward the center of rotation of the fuze, and pin hole 8 pointing toward the forward end of the fuze (direction of acceleration), thereby restraining the fuse mechanism from functioning. A pin 22 is provided to insure proper assembly and to secure the detent assembly in the above described position. In this position recess 6 is rearward with respect to the direc-

tion of motion of the projectile and radial with respect to the projectile's axis of rotation.

When the projectile is fired, plunger 14 is tilted around the forward edge of flange 16 by the acceleration of the projectile, the shank 15 tilting rearwardly with respect to the axis of the projectile but sidewise with respect to its own axis and thereby moves into recess 6 which is located rearwardly therefrom with respect to the direction of acceleration of the projectile. Simultaneously, 10 centrifugal force tends to force the tip portion 17 outwardly but this movement or full retraction is prevented when the end of the plunger lodges against the beveled shoulder 7. When the projectile leaves the gun and acceleration ceases, 15 the force of spring 29 against collar 16 pushes the collar back again flat against flange 9 thereby returning the shank 15 to its former axial relation with respect to the detent assembly and into alignment with passage 4 thereby clearing shoulder 7. By the time that this has happened the projectile has reached its full rotational speed, hence the centrifugal force resulting therefrom and acting along the axis of the detent assembly, forces the plunger outwardly against the resistance of spring 20, the beveled face of the shank portion 15 of the plunger 14 sliding up the beveled shoulder 7 and moving through the cylindrical passage 4 and the tip portion 17 withdrawing from the socket 26 in the interrupter gate 27 thus leaving the projectile free to arm by rotation of the gate about pin 34 clear of the path of pin 28.

It is obvious that the degrees of taper of the frusto-conical tip 17 and the collar 16 of the plunger 14 are governed by the clearance required as a result of the tilting motion during acceleration.

It is thus apparent that this invention provides a detent which will remain in locking position during the set-back or accelerating period of a projectile's travel but which will thereafter be released by the action of the centrifugal force of the projectile thereby permitting the fuze to arm after leaving the gun.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

I claim:

1. An arming device for a rotating projectile having an internal firing train comprising in combination, a housing having a cylindrical opening therethrough, said housing being adapted for installation in a projectile with the axis of said cylindrical opening in radial relation with respect to the projectile, the inner end thereof being adjacent the firing train, a plunger slidably engaged in said cylinder opening, a spring engaging and maintaining said plunger in a normal position axially coincident within said cylindrical opening and projecting from said housing radially inward toward the axis of rotation of the projectile and into engagement with the firing train, said plunger being adapted to secure the firing train in inoperative relation in the projectile, said housing having an arcuate recess adjoining and axially displaced from said cylindrical opening, said recess being rearwardly displaced with respect to the projectile, said recess being terminated by a shoulder at the end of said recess toward the center of the projectile,

said plunger being constructed and arranged to be tilted into said recess by the linear acceleration of the projectile and engage said shoulder, said shoulder restraining said plunger from radially outward movement during said linear acceleration, said spring returning said plunger to a position axially coincident with said passage at the termination of said linear acceleration in which position said plunger is free to retract under the centrifugal force of the rotating projectile thereby disengaging the firing train.

2. An arming device for a rotating projectile having an internal firing train comprising in combination, a housing having a cylindrical opening therethrough, said housing being adapted for installation in a projectile with the axis of said cylindrical opening in radial relation with respect to the projectile, the inner end thereof being adjacent the firing train, said cylindrical opening consisting of a chamber portion and a reduced diameter passageway in coaxial relation with each other, said passageway opening through the outer end of said housing, a plunger slidably engaged in said cylindrical opening, said plunger having a tip portion, and a shank portion, a spring engaging and maintaining said plunger in a normal position in said cylindrical passage with said shank portion in axial alignment with said reduced diameter passageway and with said tip portion projecting from said housing radially inward toward the axis of rotation of the projectile into engagement with the firing train, thereby securing the firing train in inoperative relation in the projectile, said housing having an arcuate recess adjoining and axially displaced from said passageway, said recess being rearwardly displaced with respect to the projectile, said recess being terminated by a shoulder at the outer end of said recess, said plunger being constructed and arranged to be tilted into said recess by the linear acceleration of the projectile and engage said shoulder, said shoulder restraining said plunger from radially retracting during said linear acceleration, said spring returning said plunger to a position axially coincident with said passage at the termination of said linear acceleration, in which position said plunger is free to retract under the centrifugal force of the rotating projectile thereby disengaging the firing train.

3. An arming device for a rotating projectile having a firing train, comprising in combination, a hollow cylindrical housing adapted to be mounted in radial relation on a projectile, said housing defining a central cylindrical chamber together with inner and outer reduced diameter cylindrical passages leading therefrom, all in coaxial relation with said housing, said housing having an axially offset interior recess formed therein adjacent said outer passage, thereby defining an inwardly facing shoulder relative to said projectile, a pin engaged in said housing and adapted to secure said housing with said offset recess rearward with respect to the longitudinal axis of the projectile, a plunger having a shank portion slidably engageable in said outer passage, a frusto-conical tip portion insertable through said inner passage and a collar portion therebetween of greater diameter than said inner passage, said plunger being slidably engaged in coaxial relation within said housing with said tip portion protruding from said forward end portion thereof and adapted to engage the firing train of the projectile, and a spring engaged be-

tween said collar and said housing to resiliently bias said plunger inwardly, the end of said shank portion being disposed adjacent said recess whereby said plunger may pivotally move in said housing by linear acceleration of said projectile, said shoulder abutting the outer end of said shank portion in its pivoted position to prevent radially outward movement of said plunger while said projectile is linearly accelerating.
